G. P. LACHER,
AUTOMOBILE ENGINE HOOD SUPPORT,
FILED JUNE 13, 1921.

FIG. 1.

FIG. 3.

FIG. 2.

FIG. 4.

Inventor:

George P. Lacher

by Albert Schell, Attorney

UNITED STATES PATENT OFFICE.

GEORGE P. LACHER, OF CHICAGO, ILLINOIS.

AUTOMOBILE ENGINE-HOOD SUPPORT.

Application filed June 13, 1921. Serial No. 477,339.

To all whom it may concern:

Be it known that I, GEORGE P. LACHER, citizen of the United States, residing at Chicago, Illinois, have invented certain new and useful Improvements in an Automobile Engine-Hood Support; and I do hereby declare the following to be a full, clear, and exact description of the invention, such as will enable others skilled in the art to which it appertains to make and use the same.

My invention relates to means for use with either one or both sides of the hood employed for covering an automobile engine, its general object being that of providing simple, inexpensive and easily attached means which will afford a positive and safe means for holding either one or both sides of such a hood in the opened position. Furthermore, my invention aims to provide an appliance for this general purpose which can readily be attached to an ordinary automobile, which will not interfere with the normal closing of the hood, and which can readily be adjusted to fit different makes and types of automobiles.

In automobile practice, it is customary to cover the engine with a sheet metal hood, which hood is usually constructed of hinge-jointed sections arranged symmetrically with respect to the longitudinal center line of the vehicle. In making adjustments to the engine mechanism, or when inspecting the same, it is customary to raise one lateral half of the hood out of its normal closure position and usually the raised half can be swung up over the top of the other half so as to be safely supported for this purpose. However, it is often desirable to have both sides of the hood opened at one and the same time, both for convenience in access to the engine mechanism and for affording an adequate lighting of the various parts. When this is done, the slope or curvature of the top portions of the hood usually prevents these from being held with any firmness in their raised position, so that jarring is apt to release one or both of the hood halves and to cause these to slam down substantially into their normal positions. Such a sudden closing of either side of the hood is apt to injure any one who is inspecting or adjusting the engine mechanism, and is also apt to scratch or otherwise damage portions of the hood. My invention aims to guard against such accidents by providing simple, readily attached and easily operated means for sup-

porting either one or both halves of the hood securely in the opened position. It also aims to provide a construction for this purpose which can easily be adjusted according to the requirements of various sizes and types of automobiles, which will not be in the way of the hood when the latter is to be closed, and which can readily be secured in operative position without any machining on the automobile and with the aid of such a simple tool as an ordinary screw driver. Still further and more detailed objects will appear from the following specification and from the accompanying drawings, in which

Fig. 1 is a vertical section taken transversely through the engine hood of an automobile and showing an appliance embodying my invention as it appears when retaining one-half of the hood in raised position.

Fig. 2 is an enlarged elevation of the same appliance, showing the same as it appears when adjusted for supporting both halves of the hood.

Fig. 3 is an enlarged plan view of my appliance when adjusted as in Fig. 1.

Fig. 4 is a plan view of another embodiment of my invention, namely one in which a relatively short clamping member is used for securing the main member of the appliance to the radiator rod, and in which an outward tilting of each adjustable arm of the appliance is limited by the engagement of the arm with an adjacent twist in the said main member.

In automobile practice, it is customary to mount a radiator 1 forwardly of the engine proper and to support the upper portion of this radiator by means of a so-called radiator rod 2 which extends horizontally along the axis of the vehicle from the radiator to the dashboard at some distance above the engine. This radiator rod 2 is usually in vertical alignment with the central hinge 3 of the hood used for normally covering the entire engine, and such a hood generally consists of two halves symmetrically disposed with respect to the said central hinge 3. Each of these hood halves usually consists of a top portion 4 which is curved or sloped downwardly toward the side of the vehicle, and a side portion 5 is hinged to the outer edge of the said portion 4.

Edge portions of both of the parts 4 and 5 commonly overlap stationary hood ends 15 and when either side of the hood is

opened, the hingedly connected parts 4 and 5 of the same swing with respect to each other after the manner of the closing of a jack-knife (as shown in Fig. 1) and the free 5 edge of the side portion 5 rests upon the hood ends 15. Owing to the curvature or slope of the hood ends, these do not afford firm supports for the raised hood portions as the engaged edge of the hood is apt to slide 10 along the hood end 15.

To avoid this after the manner of my invention, I mount on the usual radiator rod 2 a supporting member extending transversely of this rod and disposed entirely below the 15 top of the hood. Then I equip each end of this supporting member with means adapted to be moved into position for extending above the top of the stationary hood ends at a point laterally spaced from the central 20 hinge of the hood, so as to form a guard for preventing a laterally outward movement of the opened hood.

For example, Figs. 1, 2 and 3 show an embodiment in which the supporting member 25 of my appliance consists of two counterpart portions 6 and 7, each of which comprises a flat steel bar formed flatwise near its inner end to a V-shape and equipped at opposite sides of the said V-shaped formation with 30 perforations. The said V-shaped formations 8 cooperate in affording the opposed halves of a clamp which grips the radiator rod 2 and which can be tightened upon the latter by means of bolts 9 extending through 35 the said perforations.

Near each outer end of the parts 6 and 7, I provide each of these parts with a single 40 perforation for receiving the shank of a bolt 10, which bolt shank extends slidably through a longitudinal slot in a guard arm 11. The bolt 10 desirably is tightened by means of a wing nut 12 and I desirably provide a washer 13 between each such wing nut and the adjacent slotted arm 11. Thus 45 arranged, it will readily be seen from the left hand portion of Fig. 1 that upon loosening the wing nut 12, the adjacent slotted arm 11 can readily be dropped so that it will be entirely clear of the adjacent hood portion when the hood is closed. Likewise, 50 the right hand portion of Fig. 1 shows how the slotted guard arm 11 can be slid upwards and then clamped in position by means of the bolt 10 and the wing nut 12 so as to afford a guard for preventing the hood side 5 from sliding laterally outward along the 55 stationary hood part 15 which supports the hood side when raised. To prevent the resulting lateral thrust on the supported hood side 5 from tending to rock the guard arm 11 too much about its substantially pivotal connection to the supporting member through the adjacent bolt 10, I desirably provide the supporting member with means 60 for limiting such a pivotal movement. For

this purpose, I am here showing each portion of the supporting member as equipped at its extreme outer end with a finger 14 extending parallel to the axis of the adjacent bolt 10 and adapted to engage an edge of 70 the adjacent arm 11 after the manner shown in Fig. 2 so as to limit the outward tilting of the said arm.

With the parts thus arranged, it will be 75 obvious from the above description that the appliance of my invention can readily be attached to the usual radiator rod 2 of an automobile without requiring any machining; that the slotted guard arms 11 can readily be raised to such heights as may 80 seem necessary in connection with various shapes and sizes of hoods, and with different spacings of the radiator rods from the hood tops; also, that these arms can instantly be 85 dropped out of the way and that they can be secured against rattling by a tightening of the bolts associated with the same when the hood is to be closed. Moreover, it will 90 be evident that I accomplish my purposes without having any portion of the hood 95 engaged by screws or clamps such as might injure the finish or otherwise damage the hood, and without having any parts normally exposed where they would mar the appearance of the automobile. 95

However, while I have heretofore described my invention in a highly desirable embodiment, I do not wish to be limited to the details of the construction and arrangement thus disclosed, it being obvious that 100 the same might be modified in many ways without departing from the spirit of my invention or from the appended claims. For example, instead of constructing the main supporting member of my appliance of two 105 counterpart portions 6 and 7, I may employ a considerably longer single bar 17 after the manner of Fig. 4 and may connect both of the guard arms 11 to the latter, in which case a relatively short companion clamping 110 member 16 serves for securing the device to the radiator rod. So also, instead of employing twists in the supporting member adjacent to the central clamping, I may form twists adjacent to the free ends of this supporting bar after the manner shown in Fig. 4, and may then use the engagement of the guard arms 11 with the adjacent twists as the means for limiting the outward tilting of the guard arms. 120

I claim as my invention:—

1. The combination with the radiator rod of an automobile having a hinge-jointed hood, of a bar secured to and extending transversely of the said rod and normally disposed within the hood, and stop arm adjustably mounted on the end of the said bar and adapted in a raised position to engage a free edge of a raised hood side. 125

2. The combination with the radiator rod 130

of an automobile having a hinge-jointed hood, of a rigid bar secured to the said rod and extending transversely of the said rod below the top of the hood, a stop arm pivoted 5 to the end of the rod, and means associated with the pivotal connection for rigidly clamping the arm in position for engaging a free edge of the opened hood.

3. The combination with the radiator rod 10 of an automobile having a hinge jointed hood comprising two sections symmetrically disposed with respect to a vertical plane through the radiator rod, of a rigid bar clamped to and extending transversely of 15 the radiator rod, and independently adjustable guard means respectively mounted on the ends of the said bar and movable so as to project above the hood ends and each adapted to engage an edge portion of one 20 opened hood section.

4. The combination with the radiator rod of an automobile having a hinge-jointed hood, of a bar secured to and extending transversely of the said rod and normally

disposed within the hood, and a slotted stop 25 arm pivoted on one end of the said bar by a clamping bolt extending through the slot in the arm and adapted in raised position to engage a free edge of a raised hood side.

5. The combination with the radiator rod 30 of an automobile having a hinge-jointed hood comprising sections symmetrically disposed with respect to a vertical plane through the radiator rod of the engine, of a rigid hood-supporting bar clamped to and 35 extending transversely of the radiator rod, and a pair of rigid guard arms respectively mounted on the ends of the said bar, the said bar being disposed below the top of the hood and each of the guard arms being 40 movable with respect to the said bar from a position below the top of the hood to one in which it extends above the normal position occupied by the top of the hood.

Signed at Chicago, Illinois, June 11th, 45
1921.

GEORGE P. LACHER.
